(57) CLAIM

A novel design for a retention clip for a side window deflector, as shown and described.

DESCRIPTION

FIG. 1 is a three-dimensional view of a first embodiment of my design;

FIG. 2 is a front view of the first embodiment of my design;
FIG. 3 is a side view of the first embodiment of my design, the other side view being a mirror image of FIG. 3;
FIG. 4 is a back view of the first embodiment of my design;
FIG. 5 is a top view of the first embodiment of my design;
FIG. 6 is a bottom view of the first embodiment of my design;

FIG. 7 is a three-dimensional view of a second embodiment of my design;

FIG. 8 is a front view of the second embodiment of my design;

FIG. 9 is a side view of the second embodiment of my design, the other side view being a mirror image of FIG. 9;
FIG. 10 is a back view of the second embodiment of my design;

FIG. 11 is a top view of the second embodiment of my design; and,

FIG. 12 is a bottom view of the second embodiment of my design.
